Attorney

UNITED STATES PATENT OFFICE.

WILLIAM P. BENNER, OF SAEGERSTOWN, PENNSYLVANIA.

VISIBLE-DISPENSING CONTAINER.

1,326,837.

Specification of Letters Patent.

Patented Dec. 30, 1919.

Application filed February 2, 1917. Serial No. 146,197.

To all whom it may concern:

Be it known that I, WILLIAM P. BENNER, a citizen of the United States, and resident of Saegerstown, in the county of Crawford and State of Pennsylvania, have invented certain new and useful Improvements in Visible-Dispensing Containers, of which the following is a specification.

The present invention has reference, generally, to dispensing apparatus; and, the invention relates more particularly, to an attachment to a fluid dispensing container.

The principal object of the invention is to provide novel means for retarding or 15 breaking the force of the inflow of liquid into the container, thereby preventing splashing of the same and as a consequence, permitting the liquid to gradually attain the proper level, thus allowing the same to 20 be properly viewed by the purchaser.

All of the foregoing together with additional advantageous details and arrangement of parts of the preferred embodiments of my invention will be clear from the specific description hereinafter contained, when 25 read in connection with the accompanying drawings forming a part thereof, wherein said embodiments of the invention are illustrated for the purpose of facilitating a full 30 understanding of the present improvements.

In the drawings:

Figure 1 is a side elevation partly in section of the improved apparatus;

Fig. 2 is a top plan view of the combined 35 foraminated disk and fluid spreader and distributor.

Similar characters of reference are employed in each of the above described views to indicate corresponding parts.

Referring now more specifically to said drawings, there is provided a transparent hollow cylindrical member 1, on which member there is arranged a series of vertically disposed graduations, generally indicated by the numeral 2, these graduations indicating the quantity of liquid in the cylindrical member. A cast plate 3 is arranged over the lower open end of the cylindrical member 1 and as will be obvious, receives 45 the lowermost edges of the said member. A boss 10 is formed upon the lower face of the plate 3, and is adapted to receive a stop cock 11, whereby the outlet or egress of the fluid from the visible dispensing container 50 or receptacle may be controlled by the op-

erator or purchaser. It is to be also noted, that a plurality of apertured lugs 12 are formed upon the member 3, the purpose of which will be subsequently obvious.

A cast plate 13 of a shape and size complementary to the shape and size of the cylindrical member 1 is placed over the open top portion thereof and is provided with an annular depending flange 14, the said flange serving as means for causing the upper marginal edges of the cylindrical member 1 to closely engage the plate 13 and to prevent undue lateral movement of the same with respect thereto. It is to be noted, that the plate 13 is formed concavo-convex and is 60 provided with an eccentrically disposed boss 16, which boss has formed therein a longitudinally disposed bore, whereby the discharge portion 17 of the inlet pipe 18 may be introduced therethrough, the said discharge 65 portion extending to a point in proximity to the bottom of the container or receptacle. To permit the necessary inflow of air to the member 1, a vent pipe 16' is engaged with the plate 13 and communicates with 70 the interior of the said member. A plurality of apertured lugs 19 are formed upon the flange 14 and are vertically alined with the apertured lugs 12 upon the lower plate 3, and through which, connecting or locking 75 bolts or rods 20 are passed and supplied with locking nuts 21.

With a view toward providing means whereby fluid may be supplied to the inlet pipe 18, the said pipe is arranged vertically 80 of the cylindrical member 1 and parallel to the adjacent sides thereof, while upon the lower extremity thereof is an elbow connection 22 to which a supply pipe 31 is connected. It of course will be understood, 85 that the supply pipe 31 may be extended into engagement with any suitable source of supply, such as a liquid measuring means or the like. Stay arms 25 are arranged upon the opposite side portions of the cylindrical member 1 and are engaged therewith by passing the upper extremities of certain of the connecting bolts 20 through the apertured ends thereof, while the opposite ends of the stay arms are provided with feet 26, 100 whereby suitable fastening devices 27 such as screws or the like may be engaged with a base or wall 28. By so engaging the stay arms 25 with the upper extremity of the dispensing container 1, it will be understood, 105

that tipping or overturning of the same from various causes will be obviated, and the container will be firmly and substantially supported at all times.

5 The lower supporting member or bracket 25 is reinforced by a brake member 29. By so supporting the dispensing container, it is obvious, that the same may be readily placed in various out of the way positions and will, 10 as a consequence, require but a limited space. The discharge is threaded into the boss 16 and has turned into engagement with its screw threaded extremity a nipple 32, the lower extremity of the nipple being enlarged and provided with an annular flange whereby a similar nipple 33, also provided with an enlarged portion and a lateral flange is engaged and connected thereto through the medium of locking or connecting bolts 15 20 25 34, the bolts passing through the adjacent lateral flanges. A discharge nozzle 35 is turned into engagement with the screw threaded portion of the nipple 33 and extends downwardly into the dispensing container to a point in proximity to the bottom thereof. Within the casing formed by the nipples 32 and 33, there is arranged a foraminated disk 36, said disk being provided with apertured ears 37 for receiving the 30 locking bolts 34 therethrough and with a solid concentric raised portion 38, this por-

tion serving as a means for deflecting the flow of liquid onto the perforate portions of said disk 36. Thus, when the inflow of liquid through the supply pipes 31 18 and 17 35 is discharged onto the foraminated disk 36, the force of the same will be materially retarded or broken and hence, when the same is delivered into the discharge nozzle 35, it will be permitted to gradually ascend to the 40 various graduations upon the cylindrical member 1 and thereby facilitate the accurate reading of the quantities to be dispensed.

I claim:

In a dispensing apparatus, a dispensing 45 container, a tubular intake for said container including a vertical portion terminating within the container, a laterally enlarged chamber connected into the intake, a diaphragm within the chamber and dividing the same into upper and lower compartments, said diaphragm comprising an outer annular foraminous portion and an upwardly directed imperforate central portion, whereby the liquid flowing through the 50 55 conduit is uniformly distributed in its passage through the foraminous portion of the diaphragm.

In testimony whereof, I affix my signature hereto.

WILLIAM P. BENNER.
